[57] CLAIM

The ornamental design for a combined terminal controller and stand for a data processing system, as shown and described.

DESCRIPTION

FIG. 1 is a reduced top, front and right side perspective view of a combined terminal controller and stand for a data processing system showing my new design;

FIG. 2 is a front elevational view thereof;

FIG. 3 is a top plan view thereof, the bottom plan view being unornamented;

FIG. 4 is a right side elevational view thereof;

FIG. 5 is a left side elevational view thereof;

FIG. 6 is a rear elevational view thereof;

FIG. 7 is a reduced exploded top, front and right side perspective view thereof wherein the stand is detached; and,

FIG. 8 is a bottom plan view thereof.

FIG. 1

FIG. 2

FIG. 3

FIG. 4

FIG. 5

FIG. 6

FIG. 8
